UNITED STATES PATENT OFFICE.

WILBER J. PINE, OF KENOSHA, WISCONSIN.

WIRE FABRIC.

1,372,309.

Specification of Letters Patent. Patented Mar. 22, 1921.

Application filed June 11, 1917, Serial No. 173,953. Renewed October 11, 1920. Serial No. 416,295.

To all whom it may concern:

Be it known that I, WILBER J. PINE, a citizen of the United States, residing at Kenosha, county of Kenosha, and State of

5 Wisconsin, have invented new and useful Improvements in Wire Fabrics, of which the following is a specification.

10 My present invention relates to new and useful improvements in wire fabrics of a 10 resilient nature, and particularly adapted for use in connection with spring mattresses.

15 It is the object of my invention to simplify the structure and to increase the resiliency of spring fabrics of this nature in such manner that the yielding action of the fabric when used as a mattress conforms to the general contour of a person when lying thereon, and further in such manner that the increased resiliency does not permit an excessive general sagging of the central portion 20 of the fabric when in use, and particularly to provide a form of construction in which the transverse yielding action is confined mainly to that portion of the mattress on which a person lies, instead of occurring in the central portion to such an extent as to make it difficult for persons lying thereon to avoid sliding or rolling toward the center.

25 30 It is more particularly my object to provide an arrangement whereby the resilient yielding of longitudinal series of units in that portion of the mattress fabric on which a person lies provides for an additional transverse resilient resistance within said occupied portion of the mattress fabric to thus take up the sagging tendency of the fabric between the points of pressure afforded by the salient portions of a person's body.

35 40 With the above and other objects and advantages in view, my invention resides more particularly in the novel combination, formation and arrangement of parts hereinafter described and more particularly pointed out 45 in the accompanying claims.

In the drawings:

Figure 1 is a plan view of a portion of wire mattress fabric constructed in accordance with my invention.

50 Fig. 2 is a transverse sectional view thereof on the line 2—2 of Fig. 1.

Referring now more particularly to the accompanying drawings, the present embodiment of my improved fabric comprises a 55 series of bent wire units mutually connected longitudinally of the body of fabric when

used as a mattress, and these series of units are secured together in spaced relation by transverse tie links connected with the units at their ends.

60

Each of these units is formed of a single length of wire bent outwardly with respect to the unit at portions equally spaced from and adjacent its center to form helical coils 5, and the end sections 6 of the wire are 65 extended from these coils in crossed relation and terminate in eyes 7 disposed in planes at right angles to the planes of the helical eyes 5, and adapted for interlocking engagement with the eyes 5 of a succeeding unit, 70 the sections 6 thus extending diagonally of the unit. The intermediate portion 8 of the wire between the helical eyes 5 thus serves as a tie member for the adjacent ends of the crossed sections 6, and the other ends of 75 the sections are tied by means of their engagement in the eyes 5 of the succeeding unit. It is noted that the axes of the end sections 6 normally intersect the axes of the helical eyes 5, whereby to afford a maximum 80 resilient yielding upon stress being applied to the longitudinal series of units. The series of units are transversely connected by tie links 9, having their ends bent to form eyes 10 interlocking with the eyes 5 of the 85 units, and thus a freely flexible, strong and exceedingly simple fabric is provided.

Particularly by inwardly offsetting the sections 6 with respect to the contiguous wire portions of the helical eyes 5, whereby to dispose the axes of the sections 6 in intersecting relation with the axes of the eyes, a considerable resilient yielding may be procured in said eyes, this yielding being mainly longitudinal, and further yielding of the longitudinal series of units would, of course, be procured by means of the usual end springs (not shown) of the mattress. Upon the application of load strain to the longitudinal series of units, the sections 6 thereof would 90 tend to swing into alignment in view of their normal diagonal relation, and this action would obviously draw the eyes 5 together and procure a bowing of the intermediate tie sections 8 of the units. At the points 95 of the greatest load strain, and consequently the lowest points of the mattress, an additional resistance to this bowing tendency would be provided in a transverse direction by the tie links 9, and thus the tie portions 8 100 adjacent said points of greatest load strain would tend to retain their normally straight 105 110

shape to thus provide for an additional width of the fabric body at said points, which additional width would obviously permit a greater yielding and thus the fabric will 5 in its yielding action conform to the longitudinal contour of a person lying thereon. The tie links 9 by reason of their loose connection with the eyes 5 permit considerable free relative movement of the units, except 10 as they are involved in meeting the transverse strain, and thus do not unduly act to distribute yielding movement.

Inasmuch as the essential feature of my 15 invention resides in the provision of an arrangement wherein strains applied longitudinally to portions of the fabric provide for an additional transverse yielding of the fabric at the load points, it is obvious that various minor changes of structure may be 20 resorted to without departing in any manner from the spirit of my invention as defined in the accompanying claims.

The wire being resilient, it will be observed that each unit embodies four resilient 25 arms extending radially from a common point, intermediate of the ends of the unit where the wires are crossed. Each of these four arms also extends divergently from the arm of the next unit to which it is connected, 30 none of the connected arms being in alignment with each other. Therefore, my improved fabric is adapted to yield longitudinally by adding the yielding movement of one unit to that of the next, through the 35 longitudinal series, such yielding movement of each unit in the series being derived from the converging movements of the arms at the respective ends of the units as these arms tend to swing toward a parallel position. 40 Similarly, the units in a transverse series are adapted to expand or contract to increase or diminish the width of the fabric, the expansion being, of course, limited by the cross bars 8 and links 9, which determine the ultimate 45 width.

It will further be observed that in my improved fabric, the units are adapted to shift bodily to some extent, owing to their capability of yielding both longitudinally and 50 transversely, and owing to the fact that the units to which they are connected in both longitudinal and transverse series are also capable of yielding longitudinally and transversely.

55 I claim:

1. A resilient wire fabric, comprising the combination of transversely and longitudinally connected series of like units, each unit comprising crossed sections provided

with eyes at the respective ends of the sections, the eyes of one end of each section being connected with each other, and also connected with the eyes of transversely adjacent like units, and with the eyes of longitudinally adjacent like units, whereby the units composing each longitudinal series may yield longitudinally by drawing the ends of the unit sections toward each other subject to lateral tension exerted by the connected units of the transverse series. 60 65 70

2. A resilient wire fabric, comprising the combination of transversely and longitudinally connected series of like units, each unit comprising a single piece of wire having end eyes at one end of the unit, and having crossed sections provided with intermediate eyes at the other end of the unit, the wire composing the intermediate eyes being crossed and integrally connected between the eyes to form a flexible bow, said intermediate eyes being connected with those of transversely adjacent units by interlocking flexibly jointed links, and being also interlocked with the end eyes of the wire composing the next unit in the longitudinal 85 series, whereby the units composing each longitudinal series may yield longitudinally by drawing the unit sections toward parallel lines subject to lateral tension in the bows and cross links. 90

3. A resilient fabric comprising like units, each connected directly at its respective ends with like units in multiple series which extend both longitudinally and transversely of the fabric, and the longitudinal series of 95 units being connected transversely by tie links, each unit having resilient arms extending radially from a common point intermediate of the ends of the unit, and each arm extending obliquely with reference to the 100 arm with which it is connected, whereby the arms of the respective units are adapted for resilient spreading and contracting movements from normal position, in directions permitting longitudinal expansion and 105 contraction, and inversely permitting transverse expansion and contraction, and whereby the units are also adapted to yield bodily in any direction in the plane of the fabric, by reason of the transverse and longitudinal 110 yielding of the other like units of which the fabric is composed.

In testimony whereof I affix my signature in the presence of two witnesses.
